UNITED STATES PATENT OFFICE

ADAM WAKENSHAW, OF BEARCREEK, MONTANA

CAR COUPLER

Application filed April 3, 1928, Serial No. 267,039. Renewed October 30, 1929.

This invention relates to improvements in car-couplings and the general object is to provide a car-coupling that is automatic in its coupling action but must be manually operated to move the parts to releasing position, with the result cars are coupled thereby in a secure manner without attention, and regardless of the shock, jars or inclination of the travel of the cars, they cannot become casually uncoupled.

A further object of the invention is to provide a car coupling that can be applied to any car, is strong and sturdy, simple in construction, inexpensive to manufacture and efficient in operation and service.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a side elevation illustrating the application of my coupling to mining cars with the coupling in operative position and connecting two cars together.

Figure 2 is a rear elevation of a car showing my coupling applied thereto.

Figure 3 is a perspective view showing the coupling in position for receiving the coupling link of a companion car.

Figure 4 is a fragmentary longitudinal sectional view taken through a coupling with parts thereof in elevation.

Referring to the drawings in detail, the reference numeral 1 indicates a draw-head which is provided with the usual bore 2 and is secured to a car in any well known manner. The bore is provided with inwardly inclined side walls and bottom wall. The top wall of the draw-head has a portion thereof ar-

ranged at an inclination as indicated by the reference numeral 3 and communicating with the bore is a recess 4 formed in the top of the draw-head as best shown in Figures 1 and 4 of the drawings. The bottom wall of the draw-bar is formed with a longitudinal groove 5 extending into the recess at its rear end.

Pivots secured for rocking movement in the groove 5 is a member which includes right angled disposed arms 6 and 7. The pivot pin for the member is indicated by the reference numeral 8 and extends therethrough at the juncture of one of its arms with the other, as best shown in Figure 4. The arm 6 has a recess 9 formed in its free end and is adapted to receive the lower end of the latch arm 10 which holds the member in an operative or coupling position as clearly shown in Figure 1. The latch arm 10 is pivotally secured for movement in the recess 4 and is provided with an upper portion disposed at right angles to the arm proper, and this upper portion is provided with an opening to receive one end of a link 11 while the opposite end of said link is secured to a cross strip 12 of the operating member for moving the latch arm to a released position as shown in Figure 4.

The operating member includes a substantially U-shaped intermediate portion 13 which has secured thereto the cross strip 12, and formed with the arms of the U-shaped portion are outwardly extending oppositely disposed shanks 14 which terminate in right angle bent ends to provide handles 15.

Formed with the draw-bar adjacent the recess 4 thereof is a projection 16 having a flat face arranged in confronting relation with respect to the car and which is adapted to receive a latch member 17 to prevent movement of the operating member to its operating position as shown in Figure 4. The latch member 17 is pivotally secured to the U-shaped portion. The projection 16 is provided with a rounded wall to provide a cam 20

surface so that the latch member 17 will pass over the projection when the operating member gravitates to its inoperative position as shown in Figure 2, and when in this position the projection will prevent movement thereof as previously referred to.

The operating member is supported by strap hangers 18 secured to blocks 19 arranged on the end of the car as best shown in Figure 3, and one of these strap hangers is formed with a slot 20 through which extends a finger 21. The finger 21 is formed with one of the shanks and may be used for moving the operating member as will be apparent.

Rising from and formed with the draw-head centrally of the top thereof is an apertured ear 22 which is adapted to receive a driver's hitch whereby the cars may be propelled from place to place by animals and when it is desired to make-up large trains.

From the above description and disclosure of the drawings, it will be obvious that I have provided a car coupling that is automatic in its action for coupling-cars and due to the latching means for the coupling operated member, it will be obvious that the coupling cannot become casually uncoupled regardless of the road bed of the cars. One of my novel coupling members is adapted to be arranged on one end of a car while the opposite end is provided with the usual draw-head and coupling link, and when a companion car with its coupling link end is disposed so that the link will engage the arm 6, it will move the arm 6 to its horizontal position as shown in Figure 1 and cause the latch arm 10 to be arranged in the recess 9 of said arm 6 and movement of the operating member will be necessary in order to move the latch arm 10 out of the recess.

It is thought from the foregoing description that the advantages and novel features of my invention will be readily apparent.

I desire it to be understood that I may make changes in the construction and in the combination and arrangement of the several parts; provided that such changes fall within the scope of the appended claim.

What I claim is:

A car-coupling of the character described comprising a draw-head, a coupling link operated member pivotally secured in a groove longitudinally formed in said draw-head, substantially right angle disposed arms included in said coupling link operated member, one of said arms having a recessed free end, a latch arm pivotally mounted in a recess formed in said draw-head and being engageable in the recess of the arm to prevent movement of said coupling link operated member, operating means for said latch arm, a U-shaped intermediate portion included in said operating member, shanks formed with the arms of said U-shaped portion, strap

hangers receiving the shanks, means formed with said shanks for moving said operating member in the strap hangers, a cross strip having its ends secured to the arms of the U-shaped portion, a link connection between the cross strip and latch arm, and latching means carried by said U-shaped member and draw-head respectively to prevent movement of the operating member in one direction.

In testimony whereof I affix my signature.

ADAM WAKENSHAW.
